REELING MECHANISM

Eugene R. Ziegler, Spencerport, N. Y., assignor to
 Ritter Company, Inc., Rochester, N. Y., a corporation of Delaware

Application March 14, 1945, Serial No. 582,651

5 Claims. (Cl. 299—78)

1

This invention relates to reeling mechanisms and, more particularly, to mechanisms for reeling flexible fluid conduits such, for example, as the flexible hollow conduits employed for supplying air or water to the syringes of dental equipment stands, one object of the invention being to provide an improved device of the above character having a more simple, practical and efficient construction.

Another object is the provision of a more durable, fluid tight and reliable joint for such a device for connecting the conduit on the rotary reel with stationary fluid supply means on the reel support.

A further object is to provide a mechanism of the nature indicated in which the joint parts of the fluid supply means which move in frictional engagement with each other are accurately constructed of metal so as to resist wear for an indefinite period of use, while maintaining a fluid tight joint with low resistance to rotation of the reel.

A still further object is to provide a reeling device having the above advantages and comprising comparatively few parts so constructed and arranged as to afford a practical mechanism capable of being economically manufactured.

To these and other ends the invention resides in certain improvements and combinations of parts, all as will be hereinafter more fully described, the novel features being pointed out in the claims at the end of the specification.

In the drawing:

Fig. 1 is an elevation of a reeling device embodying the present invention;

Fig. 2 is an elevation of the same as viewed from the left in Fig. 1, partly in section and partly broken away;

Fig. 3 is an enlarged, sectional elevation substantially on the line 3a—3a in Fig. 2;

Fig. 4 is a view of parts shown in Fig. 3, detached for clearer illustration, and

Fig. 5 is an enlarged, sectional view substantially on the line 5a—5a in Fig. 2.

The invention is embodied in the present instance, by way of illustration, in a reeling mechanism for a flexible conduit for connecting a syringe of a dental equipment stand with a source of fluid under pressure located in the stand. Such a stand commonly comprises a hot air syringe, a hot water syringe and various other hand instruments supplied with operating media through extensible conducting conduits, which carry electric conductors as well as fluids and which are retracted and rewound, when not in

use, by reeling devices located in the stand. A plurality of such devices are shown in Fig. 1, comprising a reel 10 for the conduit of a hot air syringe and a reel 11 for the conduit of a hot water syringe, as well as reels, 12 and 13, for the conduits of other instruments which latter, however, form no part of the present invention, being described and claimed in the copending application of Edwin J. Wester and Eugene R.

10 Ziegler, Serial No. 582,620, filed March 14, 1945.

The reels 10 and 11 are of the same construction but opposite hand, so that a description of reel 10 will suffice for both. Reel 10 is mounted on a bracket arm 14 (Figs. 1 and 2), which is 15 suitably mounted in turn within the casing of an equipment stand. Arm 14 has fixed on its upper end a support 15, of generally cylindrical shape formed with a passageway 16, the outer end of which contains a threaded nipple 17 to 20 which is connected a pipe 18 forming part of a source of air under pressure for operating the syringe. Threaded and fixed in the opposite end of passageway 16 is a hollow, pipe-like journal 19 on which the reeling device is mounted and by means of which it is supplied with air under pressure.

Journal 19 is provided, adjacent its other or outer end, with an external annular shoulder 20 (Figs. 3 and 4), preferably in the form of an 30 integral flange, and the outer end of the journal beyond the shoulder is open to discharge the fluid transmitted through it from the supply pipe 18. The hub 21 of the reeling device is preferably 35 made of metal and comprises a portion 22 mounted for rotation on the journal, as shown, and an outer chambered portion 23, which houses the fluid tight joint hereinafter described. Hub 21 has an extended end portion 24, for connection with

40 spring means for turning the reel to wind up the conduit, as hereinafter described and has its opposite ends externally threaded, as at 25 and 26, for the reception of rings, 27 and 28, between which the reel proper is confined and clamped for rotation with the hub. The reel hub 45 comprises also a core portion 29 preferably made of insulating fiber or plastic material and opposite disk-like side walls, 30 and 31, of the same insulating material, between which the flexible instrument conduit 32 is coiled on the core 29.

50 The end of the conduit is inserted in a recess 33 in the core and attached to means on the reel and hub for connecting the conduit with the air supply passageways and with an electrical circuit for energizing the means for heating the air for 55 the syringe.

The means for connecting conduit 32 with the air and electrical supply means is best illustrated in Fig. 5, from which it will be seen that the conduit is fitted to the end of a metal tube or nipple 34, to which is connected one end of one of the circuit wires, 35, passing through the conduit to the syringe. The opposite end of nipple 34 is threadedly engaged with a metal sleeve 36 and this end of the nipple has fixed therein, as by means of interposed rubber or plastic material 37, a short metal tube 38, to which is connected the other circuit wire 39 of the conduit. The other end of sleeve 36 has fixed therein, as by means of a similar rubber or plastic composition 40, the end of a short angular length of pipe 41 having its other end fixed to and communicating with the chambered portion of the reel hub 21. It will be seen in this connection that the air supplied through the hollow journal 19 passes through the chamber 42 in the reel hub and through pipe 41, tube 38 and nipple 34 to the instrument conduit 32. Wire 39 is electrically connected with pipe 41 and to ground through the metal hub 21, journal 19, support 15 and bracket arm 14, which, in turn, is grounded on the frame of the machine. Wire 35 is electrically connected with sleeve 36 which has a projecting lug 43, extending through reel side wall 30 and into a press fit in an opening in a metal ring 44, mounted and insulated in the side wall of the reel. An insulated brush 45 contacts with ring 44 and is connected to the other side of the source of electrical energy in the stand for supplying heating current to the syringe.

The means for supplying air under pressure from the stationary journal 19 to the rotating hub 21 of the reel comprises a joint having a simple, durable and efficient construction, best shown in Figs. 3 and 4. This joint comprises a pair of cooperating metal rings, 46 and 47, surrounding journal 19 in the hub chamber 42 between the shoulder 20 of the journal and the inner end of the chamber which forms a spaced opposing shoulder 48. Ring 46 preferably has a close fit on journal 19 and is sealed to the journal and to the journal shoulder 20 by gasket means, such as a rubber gasket 49, which may be bonded to the ring and the journal surfaces to insure a more fluid tight seal. Ring 47 preferably has a loose fit on journal 19 and is sealed to shoulder 48 of the hub by gasket means, such as a rubber gasket 50. The gasket is recessed to receive the ring, as shown, and may be bonded thereto and to the hub shoulder to insure a tighter seal.

The other side faces of metal rings, 46 and 47, are finished as plane surfaces for engagement with each other, these surfaces being accurately finished with a high polish for intimate contact when pressed together, which I have found to be highly effective and durable as a liquid tight seal having a low resistance to rotation of the reel. It will thus be seen that ring 46 is stationary on the journal, while ring 47 rotates with the reel hub, and means are provided for maintaining suitable pressure of the rings against each other comprising, preferably, a helical compression spring 51, bearing at one end against the shoulder 20 of the journal and at its other end against a cap 52 engaged with internal threads at the outer end of the chambered hub portion 23, with an interposed gasket 53 for sealing the joint. The bearing portion 22 of the hub has a relatively free fit on journal 19, and spring 51 is made to apply sufficient force to move the hub

longitudinally of the journal and maintain rings 46 and 47 pressed tightly together, but free to rotate on each other. Additional pressure will be applied to these rings by the pressure of air or liquid in the chamber 42 and against cap 52, so that the greater the air or liquid pressure in the system, the tighter these rings will be pressed together.

The means for rotating the reel to rewind the conduit comprises, preferably, a spiral spring 54, housed in a cylindrical casing 55 formed at one side with an opening to receive the extended end 24 of the reel hub. The other side of the housing 55 has a collar 56, preferably formed integral therewith, in which is a set screw 57, by means of which the housing is fixed to the journal. Spring 54 has one end fixed to the hub and its other end fixed to the housing 55, the parts being assembled with the spring under tension, so that the spring turns the reel to rewind the conduit when not in use.

It will be seen from the above construction that the conduit wound on the reel is continuously maintained in communication with the source of air under pressure as the reel is rotated to wind and unwind the conduit, through joint means of simple and practical construction, which effectively seals the joint against leakage. All contact between relatively movable joint parts is confined to the precisely finished and highly polished abutting plane surfaces of the hardened metal rings 46 and 47, which are adapted to operate indefinitely with a minimum of wear such as tends to improve their seating contact with each other and their sealing efficiency. The construction interposes a minimum of frictional resistance to the free rotation of the reel in opposite directions. The conduit end is securely attached to the reel core against any derangement by unwinding tension applied to the conduit. The construction thus comprises but few parts, which are so constructed and combined as to afford a practical and efficient device which may be manufactured at low cost.

It will thus be seen that the invention accomplishes its objects, and while it has been herein disclosed by reference to the details of a preferred embodiment, it is to be understood that such disclosure is intended in an illustrative rather than a limiting sense, as it is contemplated that various changes in the construction and arrangement of the parts, as well as in the uses and adaptations of the invention, will readily occur to those skilled in the art, within the spirit of the invention and the scope of the appended claims.

I claim:

1. In a reeling mechanism, a hollow journal, a reel having a hub rotatably mounted on said journal, spaced shoulders on said hub and journal, a pair of metal rings surrounding said journal and sealed to said shoulders, respectively, said rings having finished surfaces in engagement with each other, and spring means tending to move said hub longitudinally on said journal for pressing said rings together in fluid tight engagement with each other, said hub being formed with a passageway therethrough communicating with the end of said hollow journal and provided with means for connection with a conduit wound on said reel.
2. In a reeling mechanism, a hollow journal having a discharge opening adjacent its outer end, a reel having a hub rotatably mounted on said journal, a shoulder on said journal adjacent the outer end thereof, a shoulder on said hub spaced inwardly from said journal shoulder, a pair of

metal rings surrounding said journal and sealed to said shoulders, respectively, said rings having finished surfaces in engagement with each other, and spring means engaged between said hub and journal for pressing said rings together in fluid tight engagement with each other, said hub being formed with a passageway therethrough communicating with said journal opening and provided with means for connection with a conduit wound on said reel.

3. In a reeling mechanism, a hollow journal having adjacent its outer end an external annular shoulder and a discharge opening located outwardly of said shoulder, a reel having a hub formed with an inner bearing portion rotatably mounted on said journal and with an outer chambered portion, said chambered portion having an inner end forming an annular shoulder spaced from said journal shoulder and an outer end enclosing said journal end, a pair of metal rings surrounding said journal and sealed to said shoulders, respectively, said rings having finished surfaces in engagement with each other, and spring means tending to move said hub outwardly on said journal to press said rings together in fluid tight engagement with each other, said hub being formed with a passageway therethrough communicating with said journal opening and provided with means for connection to a conduit wound on said reel.

4. In a reeling mechanism, a hub journal having adjacent its outer end an external annular shoulder and a discharge opening located outwardly of said shoulder, a reel having a hub formed with an inner bearing portion rotatably mounted on said journal and with an outer chambered portion, said chambered portion having an inner end forming an annular shoulder spaced from said journal shoulder and an outer end en-

closing said journal, a pair of metal rings surrounding said journal, gasket means sealing said rings to said shoulders, respectively, said rings having finished surfaces in engagement with each other, and a compression spring bearing against said journal shoulder and the outer end of said chambered portion for moving said hub outwardly on said journal to press said rings together in fluid tight engagement with each other, said hub being formed with a passageway therethrough communicating with said journal opening and provided with means for connection with a conduit wound on said reel.

5. In a reeling mechanism, a support having a passageway therethrough provided with means for connection with a source of fluid, a hollow journal fixed in said support and communicating with said passageway, said journal having adjacent its outer end an external annular shoulder and a discharge opening located outwardly of said shoulder, a reel having a hub formed with an inner portion rotatably mounted on said journal and with an outer chambered portion, said chambered portion having an inner end forming an annular shoulder and an outer end enclosing said journal end, a pair of metal rings surrounding said journal, gasket means sealing said rings to said shoulders, respectively, said rings having finished surfaces in engagement with each other, and a spring bearing against said journal and the outer end of said chambered portion for moving said hub outwardly to press said rings into fluid tight engagement with each other, said chambered portion forming a passageway in said hub which communicates with said journal discharge opening and is provided with means for connection with a conduit wound on said reel.

EUGENE R. ZIEGLER.
